UNITED STATES PATENT OFFICE.

DAVID CHAPPELL, OF LLANELLY, ENGLAND, AND JOHN CHAPPELL, OF PITTSBURG, PENNSYLVANIA.

LIFE-SAVING DEVICE FOR SUBMARINE VESSELS.

1,002,033.

Specification of Letters Patent. Patented Aug. 29, 1911.

Application filed May 27, 1911. Serial No. 629,938.

To all whom it may concern:

Be it known that we, (1) DAVID CHAPPELL and (2) JOHN CHAPPELL, (1) a subject of the King of Great Britain, (2) a citizen of the United States of America, residing at (1) Llanelli and (2) Pittsburg, in the counties of (1) Carmarthen and (2) Allegheny, (1) Wales, England, and (2) Pennsylvania, have invented certain new and useful Improvements in Life-Saving Devices for Submarine Vessels, of which the following is a specification, reference being had therein to the accompanying drawing.

This invention relates to a life saving device for submarine vessels, and the primary object of the invention is to furnish a vessel, boat or other marine craft with a detachable and auxiliary air tight boat that can be released from the main vessel to save the lives of the occupants of the vessel.

Another object of this invention is to provide a life boat that can be advantageously used in connection with submarine and battle ships, the boat being arranged in the vessel whereby it can be easily and quickly released by the occupants thereof, when an accident occurs to a submarine boat or when a vessel equipped with an tight compartment or chamber is sunk.

A further object of this invention is to furnish a marine craft with a life saving boat that can be easily and quickly released from the marine craft without the craft being damaged by the in-flow of water or other matter.

With the above and other objects in view the invention resides in a novel construction, combination and arrangement of parts to be hereinafter specifically described and then claimed.

Reference will now be had to the drawing wherein like numerals of reference designate corresponding parts throughout the several views, in which:—

Figure 1 is a diagrammatic elevation of a submarine vessel provided with two life saving boats, Fig. 2 is a similar view showing the submarine vessel provided with a single life saving boat, Fig. 3 is an enlarged longitudinal sectional view of a portion of the submarine vessel provided with the life saving boat, and Fig. 4 is a cross sectional view of the same.

As illustrated in Figs. 1 and 2, the submarine vessel 1 can be provided with one or

more life saving boats. In Fig. 1 the life saving boats are arranged fore and aft of the conning tower 2, and in Fig. 2 of the drawing the life saving boat is provided with a conning tower. The shell of the vessel 1 has an oblong opening 3 and the material bordering upon the edges of said opening is reinforced, as at 4 and provided with a seat 5 for a resilient gasket or packing 6. Formed integral with the reinforced edges 6 of the opening 3 is a depending casing 7 having the front and rear walls 8 thereof provided with bearings 9 having screw threaded bores 10. The bottom 11 of the casing has bearings 12 and a manhole 13, said manhole being normally closed by a trap door 14.

Seated upon the gasket 6 is the top plate or cover 15 of a life saving boat 16. The upper edges of this boat are adapted to snugly fit in the opening 3 and the gasket 6 provides an air tight and waterproof connection. The end walls 17 of the life saving boat are provided with bosses 18 and adjustably mounted in said bosses are anchoring screws 19 adapted to engage in the bearings 9 and anchor the boat within the casing 7, whereby during the maneuvering of the vessel 1 said life saving boat cannot become accidentally displaced.

The rear wall of the boat 16 is provided with a rudder frame 20 for a pivoted rudder post 21 and a rudder 22. Extending through the rear wall is a propeller shaft 23 having a propeller 24 and said propeller shaft is adapted to be revolved by a motor 25 or other source of power.

The bottom of the life saving boat 16 is provided with a manhole 26 normally closed by a trap door 27. Adjacent to the manhole 26 are bosses 28 having releasing screws 29. These screws are adapted to engage the bearings 12 of the casing 7 and elevate the life saving boat when the screws 19 are moved out of engagement with the bearings 9.

Besides the life saving boat being equipped with propulsion means, the boat can always be equipped for immediate use with such supplies as are necessary for the maintenance of life.

When the submarine vessel 1 or any other vessel equipped with the life saving boat is sunken and cannot rise to the surface of the water, the occupants of the vessel open

the trap doors 14 and 27 and enter the boat 16. The trap doors 14 and 27 are then closed, the anchoring screws 19 unanchored are moved out of engagement with 5 the bearings 9, and then the releasing screws 29 are rotated to lift the life boat 16 and unseat the same relatively to the gasket 6. The water rushing in the opening 3 immediately fills the casing 7 and when the boat 10 16 is released it ascends to the surface of the water.

In order that a fresh supply of air can be obtained by the occupants of the boat 16, the top plate or cover 15 is provided with 15 a manhole 30 normally closed by a trap door 31. When the surface of the water is reached the trap door can be opened, observations made, and the propulsion means immediately placed in operation to propel the life saving boat toward shore or a vessel in the 20 vicinity of the accident.

From the foregoing it will be observed that the release of the life saving boat does not allow water to enter the submarine vessel, consequently the vessel will remain intact until raised. The casing 7 is therefore an essential element to the successful use 25 of the life saving boat.

While in the drawing there is illustrated 30 a preferred embodiment of the invention, it is to be understood that the structural elements thereof are susceptible to such changes as fall within the scope of the appended claims.

35 What we claim is:

1. In a life saving device the combination with a vessel having an opening formed thereof, of a casing suspended from the

edges of said opening, bearings carried by said casing, a life boat fitted in the opening 40 of said vessel, anchoring screws carried by said life boat and engaging in some of the bearings of said casing, releasing screws carried by said life boat and engaging the other of said bearings and adapted to raise 45 said life boat, said life boat and said casing having manholes formed therein, trap doors normally closing said manholes, a top plate carried by said boat and having a manhole formed therein and a trap door normally 50 closing said manhole.

2. In a life saving device for vessels, the combination with a vessel having the shell thereof provided with an opening, of a casing suspended from the edges of said opening, a life boat fitted in said opening and having the top thereof closed, anchoring screws carried by said life boat for retaining said life boat in said casing, releasing screws carried by said life boat and adapted 55 to elevate said life boat relatively to said casing, said casing, life boat, and the closed top thereof having manholes formed therein, and trap doors normally closing said manholes, substantially as described. 60

In testimony whereof we affix our signatures in the presence of two witnesses.

DAVID CHAPPELL.
JOHN CHAPPELL.
